UNITED STATES PATENT OFFICE

CONSTANTINE N. NEKLUTIN, OF FERGUSON, MISSOURI, ASSIGNOR TO THE UNIVERSAL MATCH CORPORATION, OF ST. LOUIS, MISSOURI, A CORPORATION OF DELAWARE

DISPENSING MACHINE

Application filed April 15, 1929. Serial No. 355,257.

This invention relates generally to dispensing machines and, more particularly, to a certain new and useful improvement in machines adapted combinedly for the dispensing of articles and the display of advertising posters and the like.

My invention has for its prime object the provision of a machine adapted for exhibiting one by one in succession for visual inspection respective advertising displays or the like of a series, and combinedly dispensing simultaneously upon each such respective exhibition a useful or desired article or commodity.

My invention has for another object the provision of such a machine that is especially adapted for the dispensing of paper matches, such as are commonly put up in so-called books or packets, although the machine may also be employed for the dispensing of other like articles of merchandise, such as, for instance, boxes of matches, by simply varying the proportions of the machine.

My invention has for still another object the provision of such a machine characterized by having a plurality of magazines for the storage of the merchandise or articles to be dispensed, the machine delivering from each magazine, in turn, one of the articles carried in the respective magazines, on the manual manipulation of a suitably handled lever operatively associated with the several magazines for bringing the latter, in turn, into registration with the delivery chute of the machine, the dispensed article being automatically discharged from said magazine into said delivery chute as said magazine is moved over the delivery chute.

My invention has for a further object the provision of such a machine in which advertising displays are presented to view in sequence as the magazines of the machine are successively advanced step by step for discharge of their contents, so that, by providing a different display on each card, the advertising value thereof is greatly increased both by reason of the variety of advertising offered and the moving or changing sequence thereof.

My invention has for a still further object the association with the machine of a coin-

controlled device characterized by an extremely simple construction, the coin-controlled apparatus having a single tilttable coin-receiving member normally obstructing the operative movement of the operating lever of the machine unless a coin of a size greater than a predetermined diameter is inserted into said member, the latter being associated with a stop for limiting the tilting movement of said member, so that an oversize coin in the coin-receptive member will likewise obstruct the movement of the machine-operating lever, whereby the machine is operative only upon the insertion in the coin-receiving member of a coin of a predetermined size, or more particularly, of a selected diameter.

My invention has for still further objects the provision of such a machine which may be inexpensively manufactured, which is simple and compact in construction, which is conveniently and readily operable, and which is efficient in the performance of its intended functions, and to improve generally upon machines of the class described.

And with the above and other objects in view, my invention resides in the novel features of form, construction, arrangement, and combination of parts hereinafter described and pointed out in the claims.

In the accompanying drawings:

Figure 1 is an elevational view of a dispensing machine embodying my invention;

Figure 2 is a sectional plan view thereof taken approximately along the line 2—2, Figure 1;

Figure 3 is an enlarged sectional plan view of the machine taken approximately along the line 3—3, Figure 1;

Figure 4 is an enlarged vertical sectional view of the machine, parts thereof being broken away and in section;

Figure 5 is a further enlarged detail of the latch-lever and associated parts, other parts of the machine being broken away and omitted;

Figure 6 is a sectional plan view approximately along the line 6—6, Figure 1;

Figure 7 is an enlarged fragmental detail of a portion of the parts shown in Figure 6;

Figure 8 is a fragmentary sectional view approximately along the line 8—8, Figure 6;

Figure 9 is a fragmentary detail view showing one of the magazines in registration with the delivery chute, the feeder-arm being in the act of feeding a book of matches into said chute;

Figure 10 is a plan view similar to Figure 6, parts thereof being broken away, showing a coin controlled mechanism associated with the machine;

Figure 11 is a vertical sectional view approximately along the line 11—11, Figure 10, showing the normal locking-position of the coin-receiving member; and

Figure 12 is a view similar to Figure 11, showing a coin positioned in the coin-receiving member, the latter being tilted to permit the movement of the operating lever thereover.

Referring now more in detail and by reference characters to the drawings, which illustrate a preferred embodiment of my invention, the machine includes a suitable preferably annular base or stand 1, preferably integral with which is a series of ribs 2 radiating from a central hub-member 3. Mounted at its lower margin, as at 4, upon the base 1, is the upstanding shell or casing 5 of the machine, the shell 5 having a roof 6 preferably formed centrally with a dome 7.

Fixed at its lower end in the hub-member 3 and having its upper end disposed in the dome 7, as best seen in Figure 4, is an upstanding shaft or post 8.

Having a hub-portion 9 journaled for oscillation on the shaft 8 with sliding bearing contact with the top of the hub-member 3, is a horizontally swingable operating-lever 10, whose handle-portion 11 projects for movement and for convenient lever-manipulation, outwardly through a suitable slot 12 formed horizontally for the purpose in the base 1.

Freely rotatable about the shaft 8 and supportingly bearing on the top of an anti-friction plate 13 resting on the top of the hub-portion 9 of the lever 10, is a feeder-plate 14 having a plurality of upstanding walls 15, 15, outwardly beyond which extend an equal number of feeder-shelves 16, 16. The walls 15, 15, which are each medially divided by a vertical slot 17, in the present instance are four in number, each wall 15 supporting, as by rivets 18, 18, or other suitable fastening means, the inwardly returned ends of a tubular magazine or merchandise holder 19, there correspondingly being, in the present instance, four such merchandise holders or magazines, each having a contour in plan suitably shaped and proportioned to the article to be dispensed or vended. Thus the magazines 19 may each be of different dimensions in cross-section and may be circular, rectangular, oblong, square, oval, or any other shape, although in the machine illustrated, which is adapted to dispense or vent matchbooks 20, as shown, the said magazines are each correspondingly of a rectangular cross-section.

In the present machine also, the magazines or merchandise holders 19 are disposed in quadrature relatively to the feeder-plate 14, the walls 15, 15, being preferably united at their corners to provide a rigid structure, as clearly shown in Figure 3. The inwardly returned ends of each respective magazine 19 are spaced, in registration with the slot 17 in the adjacent wall 15, to provide a slot 21 extending longitudinally throughout approximately the length of the magazine, for a purpose presently appearing, and in the outer or front wall of each magazine 19 is a corresponding longitudinal slot 22, preferably formed by striking out of the material of the magazine frontal wings or outstanding legs 23, which serve to stiffen the magazine structure as a whole.

The magazines 19 each extend upwardly from the feeder-plate 14 a suitable distance proportionately to the desired storage capacity of the machine. At their top, each magazine 19 is open for stocking purposes, and for feeding purposes, each of the feeder-shelves 16 is adapted to register with, and at the bottom of, a respective magazine 19 for supporting the column of merchandisable articles 20.

As best seen in Figure 9, the lower edges or delivery lips 24 of the respective magazines 19 are spaced from the respective feeder-shelves 16 to provide a feed-slot 25 suitably to permit the lateral movement therebetween of as many of the articles carried in the magazines as may be desired to be vended or dispensed at each operation of the machine. In the present instance, one book of matches 20 is intended to be delivered from each respective magazine in sequence as the feeder-plate 14 is rotated, as will presently more particularly appear.

As each article 20 to be vended or dispensed is slid or shifted laterally through the feed slot 25 from beneath the superimposed column of like articles in the magazine, the article so laterally moved is dropped into a delivery chute 26 supported in any suitable manner for registration with a frontal delivery opening 27 provided in the base 1 (Figures 1 and 3). For this purpose, the feeder-shelves 16 are not co-extensive with the cross-sectional area of the respective magazines, but extend over approximately the leading half, with respect to the movement of the magazine, of the lower or discharge opening thereof. In this way, sufficient space or clearance is provided between the consecutive feeder-shelves 16 to permit the discharge of the vended or dispensed article therebetween.

Fixed in the horizontal plane of the feed-slots 25, for obstructively engaging the successive respective lowermost articles 20 in the several magazines 19, is a feeder-arm 28 up-standing from one of the radiating ribs 2 of the base 1, as best seen in Figures 4 and 9. The feeder-arm 28 is disposed on the farther side of the delivery-chute 26 with respect to the rotatory movement of the magazines 19 thereover, and its purpose or function is to cause the said successive respective lowermost articles 20 in the respective magazines 19 to be slid or shifted off its respective feeder-shelf 16 into the delivery chute 26 as the magazines 19 are moved therewith, which movement is accomplished by manual manipulation of the swingable operating-lever 10 and its co-operating-members, now to be described.

Depending from the feeder-plate 14, is a plurality of dogs or catches 29, there being as many of said catch-dogs 29 as there are magazines 19. Swingably mounted on a post 30 up-standing from one of the radiating ribs 2 of the base 1, is a latch-lever 31 provided at its free end with a notch, as at 32, the lever 31 being normally tensionally swung inwardly, as by a spring 33, for yielding detachable engagement at its notch 32 with an adjacent catch-dog 29. It follows that, when a catch-dog 29 is engaged by the latch-lever 31, the feeder-plate 14 is latched against rotation, and the parts are preferably disposed so as to stop and retain the feeder-plate 14 and its carried magazines 19 in the position thereof best seen in Figure 3, that is to say, just after an article 20 to be vended or dispensed has been discharged from one of the respective magazines 19 into the delivery chute 26.

Working in an arc-shaped groove 34 formed in the latch-lever 31 and pivotally spring-set on an arm 35 of the operating-lever 10, as best seen in Figures 6 and 7, is a latch-releasing pawl 36 adapted, on swinging movement of the lever 10, to yieldingly engage a shoulder 37 on the outer end of the latch-lever 31. Continued swinging movement of the lever 10 will cause the pawl 36 to pivot on the arm 35, thereby causing the latch-lever 31 to swing about its pivot-point and be disengaged from the particular catch-dog 29 caught in the latch-notch 32, so that the feeder-plate 14 and its carried magazines 19 may be free for rotation.

Spring set on a bracket 38 preferably up-standing from the operating lever 10 and having its free end normally spaced from the adjacent catch-dog 29, as seen in Figure 7, when the feeder plate 14 is latched against rotation, is a detent pawl 39 adapted to impinge said adjacent catch-dog 29 just after the latch lever 31 has been released from its adjacent catch-dog 29. In the present machine, the detent pawl 39 is oppositely disposed to the latch-pawl 36, suitably to the

conformation of the operating lever 10, but this arrangement is only a matter of convenience.

It will be readily seen then that a portion of the movement of the operating lever 10 from its neutral position is employed to unlatch the feeder-plate 14. Thereafter, continued movement of the operating-lever 10 will cause the detent pawl 39 to engage the feeder-plate 14 to rotate the same in a manner to cause one of the magazines 19 to traverse the delivery chute 26, with consequences as previously set forth, that is to say, the discharge from a magazine 19 of one or more of the articles of merchandise being vended or dispensed, as desired or determined by the proportions of the several parts of the machine.

However, as the movement of the operating-lever 10 is continued, the pivotal movement of the swingable latch releasing pawl 36 will ultimately bring the same to a point where it will no longer engage the shoulder 37 on the latch lever 31, resulting in the disengagement of the pawl 36 from the lever 31, so that the latter may swing back, urged by or under the tension of the spring 33, towards the now approaching catch-dog 29 that is next in sequence on the feeder-plate 14, the next catch-dog 29 being, in turn, caught by the latch-lever 31, thereby stopping rotation of the feeder-plate 14, with the magazines 19 carried thereby in the same relative position with respect to the delivery-chute 26 as before, except, of course, that they have all been moved one step forward in sequence.

Upon completion of the operating movement of the lever 10, the operator releases the same, which is thereupon yieldingly returned to its starting point or neutral position by means of a spring or like tensional device 40, the latter being mounted in any suitable manner, or, as shown, it may comprise a coil spring wrapped around the hub 3 of the base 1, with one end bearing against one of the ribs 2 of the base and the other end bearing against the lever 10.

Upon the return of the lever 10 to neutral position, the detent pawl 39 yieldingly slides under the catch-dog 29 next in sequence and resumes its described position as at the beginning of the operating movement of the lever 10. Meanwhile, the latch-releasing pawl 36 travels past the shoulder 37 on the latch-lever 31 and moves through the arcuate groove 30 therein to resume its normal position, in preparation for another operation of the lever 10.

While the lever 10 has been described as freely movable on manual manipulation thereof, in Figures 10 to 12, inclusive, I show releasable means for obstructing the movement of the operating lever 10 by a coin controlled mechanism now to be described.

Having a shoulder 41 normally disposed

in the path of travel of the operating lever 10, is a tiltable coin-receiving member or detent 42 pivotally mounted, as at 43, on a post 44 upstanding from a floor or support 45 suitably mounted on the base 1, or, as in the present instance, forming an extension of the delivery-chute 26 and having upstanding walls 46, 46, providing a box-like coin receptacle 47.

An arm 48 on the tiltable member or detent 10 normally impinges a stop 49 provided on the post 44, for limiting the upward tilting movement of the detent 42, which latter is yieldingly normally urged upwardly by a spring or like tensional member 50, which has one 15 end bearing on the support 45 and the other end bearing on the underside of the detent 42.

The coin-receiving detent 42 is provided with a coin recess 51 opening through the meeting upper and end faces 52, 53 thereof for 20 the reception of a coin through the upper face 52, and the discharge thereof, as presently appearing, through the end face 53 into the coin receptacle 47. The inner walls of the recess include a shelf 54 for the repose of a 25 coin 55 thereon when the detent 42 is in its normal position, that is to say, when the shoulder 41 will obstruct the movement of the operating lever 10 therewith, as shown in Figure 11.

30 A coin-chute 56 is mounted in the machine in any suitable manner, so as to clear the moving parts thereof, and serves to guide the deposited coin 55 for lodgement in the coin-recess 51 of the coin-receiving-member 42, 35 said recess 51 being proportioned suitably to the size of the coin intended to co-operate with the coin-receiving member 42 for tilting the latter to clear the lever 10, as presently appearing.

40 The inner vertical wall 57 of the recess 51 is normally spaced from the adjacent edge of the operating lever 10 when the latter is in its neutral position, so that a coin deposited in said recess may rest thereon. Such a coin, as 45 55, will, if of the selected dimensions stated, project sufficiently above the advancing face 58 of the lever 10 to be engaged thereby on movement thereof, the lever 10 impinging the 50 arcuately presented edge of the coin to ride thereover, thereby forcing the coin downwardly against the ledge or shelf 54 and tilting the member 42 sufficiently to depress the shoulder 41 to clear the lever 10, the portion of 55 the latter at this point being wide enough to continue to engage the edge of the coin until the face 58 has passed the shoulder 11.

Further movement of the lever 10 will release the coin 55, but the member 42 will 60 continue to be depressed until the lever 10 has passed therebeyond, during which time the coin 55 will roll off the now sloping shelf 54 into the coin receptacle 47, the member 42 projecting, for this purpose, through a 65 slot 59 in one of the walls 46 of the receptacle

47, the lower wall of the slot 59 preferably forming a stop, as at 60, for limiting the downward tilting movement of the member 42.

The stops 49 and 60 co-operate with the member 42 to limit the tilting movement thereof, which limit may be predetermined suitably to the size of the coin intended to operate the device. The stop 49, by limiting the upward tilting movement of the member 42, will cause the shelf 54 to be positioned so that only a coin having a diameter greater than a predetermined diameter will be engaged by the lever 10, smaller coins passing, usually, through the recess 51 into the receptacle 47, and the member 42 will not be tilted sufficiently to clear the lever 10. The lower stop 60 limits the downward tilting movement of the member 42, so that a coin having a size greater than the predetermined diameter will not clear the lever 10, thereby obstructing the passage of the same and preventing the further operation of the device.

Thus the tiltable member or coin-receiving detent 42 normally obstructs the movement of the lever 10 therewith except upon the insertion of a coin of proper size in the detent; likewise, an oversize coin will obstruct the movement of the lever 10 therewith, irrespective of the position of the detent. Hence, in a single tiltable detent, co-operating with suitable stops, I provide a coin-controlled mechanism operative to prevent the manipulation of the machine except upon the deposit of a proper coin therein.

Sometimes the articles of merchandise 20 in the respective magazines 19 are of such a character that they will not properly feed onto the feeder shelf 16, and it is desirable 105 that a weight or the like be provided to press the articles 20 firmly downwardly therein. For this purpose, I provide a weight 61, having dimensions in plan slightly smaller than the cross-sectional dimensions 110 of the respective magazines 19, so that the same may accommodate itself to the surface of the uppermost one of the articles 20, in the magazine, against which the weight will 115 bear. In the present instance, the weight 61 will so accommodate itself by a rocking movement in the magazine, inasmuch as the present books of matches 20 are usually made in a somewhat triangular cross-section; consequently the upper surface of the topmost 120 book will be first inclined in one direction, and then, after the discharge of the lowermost book from the magazine, said upper surface will incline in the other direction.

However, it is desirable that the weight 61, while so rockable, should not be shiftable as a whole in the magazine, as otherwise undesirable noises are made when the magazines are rotated. For this purpose, the weight 61 is provided with oppositely 130

disposed obliquely upwardly and outwardly presented flanges or walls 62, as best seen in Figure 9, so that, while the weight 61 may rock in the magazine, the free edges of the flanges 62 will substantially continuously engage the opposite side walls of the magazine, thereby preventing the shifting of the weight as a whole therein. And in order that the weight 61 may be readily removed from the magazine, handles 63 are provided on the weight, which handles project suitably through the respective slots 21, 22, in the opposite front and rear magazine walls.

Marginally secured to the inner or rear walls of the respective upstanding magazines 19, at the top thereof, and journaled on the shaft 8, is a top bearing plate 64 guidably supporting the upper end of the magazine assembly for rotation about the shaft 8. The plate 64 carries a friction plate 65 co-operating with a friction plate 66 fixed against rotation on the shaft 8, but axially shiftable thereon. A spring 67 or like tensional member is mounted over the shaft 8, with one end bearing against the plate 66 and the other end bearing against a retainer plate or washer 68 held in place on the shaft 8 by means of a suitable fastening device, as a cotter 69. The friction plates 65 and 66 co-operate to prevent the too rapid turning of the magazine assembly when the machine is in operation.

The casing 5 and its roof 6 are constructed preferably as a one piece stamping of dimensions to house the several magazines 19, as best seen in Figures 4, and also housed in the shell 5, surrounding the assembly of magazines 19, and having notches 70 in its lower margin for the reception therein of supporting lugs or arms 71 projecting from the respective magazines 19, is a cylindrical frame or drum 72 adapted for rotation with in the casing 5 with the magazine assembly.

Integrally formed laterally extending wing-like struck-out portions 73 are located in spaced pairs of vertical rows around the outer perimeter of the drums 72, each pair of wings 73 forming a retaining means for a display card or poster 74, the side marginal edges thereof being inserted under the respective wings of the pair and over the perimeter of the shell between said pair of wings. The wings 73 are located with respect to the magazine assembly so that, when the latter is latched against rotation, that is to say, is in a neutral position, a display card 74 will register with and be visually exhibited through a glazed frontal window 75 provided in the housing 5, as best seen in Figure 1.

There are, in the present instance, four display-cards 74 thus mounted on the drum 72 for presenting to the window 75 a plurality of displays in sequence as the magazines 19 of the machine are successively rotatorily advanced step by step, so that, by providing a different display on each card 74, the advertis-

ing value thereof, in association with the vending or dispensing properties of the machine, is greatly increased both by reason of the variety of advertising offered and the moving or changing sequence thereof.

The lowermost one in each of the rows of wings 73 is preferably formed in a manner best seen in Figure 3, so as to force the side margins of the particular poster to bear against the horizontal wall of the slot in the drum 72 formed by striking out the wings; in this manner, the poster 74 is retained against slipping downwardly through the wings. As best seen in Figure 4, a ring-like member or cap 76 is detachably mounted upon the drum 72, the ring 76 having a depending annular flange 77 adapted to receive the upper margins of the posters for retaining the same in position on the drum 72.

The construction and use of the machine having been made clear as the description thereof has proceeded, it will be seen that I have accomplished the objects of the invention in a very simple and effective manner, that the separately moving parts are relatively few in number, compared with the complexity of the usual machine of the present class, and that the coin-controlled mechanism is particularly simple and has, in fact, practically only one moving member, with the result that the machine is easy to maintain in operating condition, is not expensive to manufacture, and is relatively light in weight.

By simply removing the shell 5 and the drum 72, the magazines 19 may be readily re-filled or restocked; and by removing the cotter 69, the entire magazine assembly including the feeder-plate 14 and its carried magazines 19, may be shifted off the shaft 8 for access to the operating mechanism on the base 1. In like manner, access to the display cards 74 may be readily attained by simply removing the housing 5 and the ring cap 76.

In actual practice, the machine has proven to be strong and reliable in operation and will dispense its contained articles of merchandise in the manner described in a highly satisfactory manner. Such machines are commonly placed in public places, where they are subject to abuse of all sorts, and the characteristics enumerated are, therefore, of great value in this class of devices, removed, as they are, from adequate supervision of competent mechanics or suitable maintenance service, except at long intervals.

While I have shown and described the preferred embodiment of my invention, it will be readily understood that changes and modifications in the form, construction, arrangement, and combination of the several parts of the machine may be made and substituted for those herein shown and described without departing from the nature and principle of the invention.

Having thus described my invention, what I claim and desire to secure by Letters Patent is:

1. In a machine of the class described, the combination with a rotatable feeder plate and a plurality of article containing-magazines carried by the plate, of means for rotating said feeder-plate in step-by-step relation corresponding to the intended dispensing of articles from the respective magazines in succession, said means including a plurality of dogs mounted on the feeder plate, each of said dogs corresponding to one of the magazines, a swingable latch lever mounted in operative adjacence to the path of movement of said dogs, said lever having a latch notch at its free end adapted to engage each of said dogs in sequence, an operating lever swingable about the center of rotation of said feeder plate, a latch pawl pivotally spring set on said operating lever, said latch lever having an arcuate way for the movement of said latch pawl therein, said arcuate way terminating in a shoulder for engaging said latch pawl on movement of said operating lever in one direction, said latch pawl pivoting on said operating lever to disengage said latch lever from its engaged dog, and a spring set detent pawl pivotally mounted on said operating lever adapted to engage another of said dogs on movement of said operating lever in said direction.

2. In combination, in a machine of the class described, a base, a post upstanding from the base, a drum journaled for rotation on the post, means for effecting rotary movement of the drum, and means for yieldingly retarding rotary movement of the drum, said last named means including a plate disposed about the post and having engagement with a wall of the drum, a second plate fixed on the post, and a spring interposed on the post between said plates and yieldingly engaging against the first one thereof.

3. In combination, in a machine of the class described, a base, a post upstanding from the base, a plate mounted on the post for horizontal rotary movement relatively to the base, an annular series of spaced catch-dogs on the plate, a notched latch pivotally mounted on the base and laterally swingable relatively to the plate for releasable engagement with the successive dogs for latching the plate against rotary movement, and means for effecting dog-release of the latch and step-by-step rotary movement of the plate, said means including an operating lever pivoted on the post for oscillation in a horizontal plane relatively to the plate, a first pawl pivotally mounted on the lever for dog-releasing actuation of the latch, and a second pawl on the lever for plate-actuating engagement with the successive dogs.

4. In combination, in a machine of the class described, a base, a post upstanding from the

base, a plate mounted on the post for horizontal rotary movement relatively to the base, an annular series of spaced catch-dogs on the plate, a spring-set notched arcuate latch pivotally mounted on the base and laterally swingable relatively to the plate for releasable engagement with the successive dogs for latching the plate against rotary movement, and means for effecting dog-release of the latch and step-by-step rotary movement of the plate, said means including an operating lever yieldingly pivoted on the post for oscillation in a horizontal plane relatively to the plate, a first spring-set pawl pivotally mounted on the lever for dog-releasing actuation of the latch, and a second spring-set pawl on the lever for plate-actuating engagement with the successive dogs.

5. In combination, in a machine of the class described, a base, a post upstanding from the base, a feeder-plate mounted for horizontal rotary movement relatively to the base, a plurality of article magazines carried by and upstanding from the plate and each having a discharge-slot, means for rotarily actuating the feeder plate and its carried magazines, said means including an annular series of dogs disposed on the plate in spaced relation corresponding to the respective magazines, a notched arcuate latch pivotally mounted on the base and laterally swingable relatively to the plate for engaging the successive dogs for latching the plate against rotary movement, an operating lever mounted on the post for oscillation in a horizontal plane under the plate, and a pair of spring-set pawls pivoted on the lever for respectively actuating the latch out of plate-latching engagement with the dogs and for plate-actuating engagement with the respective dogs, and an article-discharging arm fixed on the base in the plane of the magazine-slots.

In testimony whereof, I have signed my name to this specification.

CONSTANTINE N. NEKLUTIN.
